UNITED STATES PATENT OFFICE.

FREDERICK M. LASERSON, OF BROOKLYN, NEW YORK, ASSIGNOR, BY DIRECT AND MESNE ASSIGNMENTS, OF ONE-HALF TO LAWRENCE M. STEIN, OF CHICAGO, ILLINOIS, AND ONE-HALF TO WADE STEVENSON, OF BUFFALO, NEW YORK.

GARMENT-MARKING MACHINE.

Application filed August 25, 1920. Serial No. 406,010.

To all whom it may concern:

Be it known that I, FREDERICK M. LASERSON, a citizen of Great Britain, and resident of Brooklyn, in the county of Kings and 5 State of New York, have invented certain new and useful Improvements in Garment-Marking Machines, of which the following is a specification.

This invention relates to improvements 10 in garment marking machines. More particularly the invention relates to marking machines for marking the position of pockets, lapels, button holes and the like on garments before they are sewed. The 15 particular object of the invention is to provide a marking machine of simple and practical construction and design whereby garments may be marked by means of stitches to indicate the position of pockets and the 20 like as stated above.

Marking machines are known to the art in which the markings are done by means of perforations. Such marking is, however, unsuitable for certain fabrics which may 25 be too soft so that perforations do not "stay," or which fabrics may be of a kind in which the perforations show up too prominently.

It has therefore been proposed to mark 30 garments by sewing a stitch of thread through layers of fabric at the point desired and thereafter cut the thread between the layers, or on both sides of each layer, so as to leave a bit of thread to indicate 35 the desired position.

As stated it is the object of this invention to provide a stitch marking machine to do the work as aforesaid.

To this end my invention comprises a 40 stitch marking machine arranged and constructed as hereinafter set forth, while reference is had to the accompanying drawing, in which—

Fig. 1 is a side view of a stitch marking 45 machine with parts shown in section.

Fig. 2 is a view of the treadle arrangement for the machine, said figure being a continuation of Figure 1.

Fig. 3 is a fragmentary plan view of 50 parts shown in Figure 1.

Fig. 4 is an end view of the machine shown in Figure 1.

Fig. 5 is a fragmentary plan view of the machine showing a modification.

Fig. 6 shows the point of the needle used 55 in connection with the machine in Figure 5.

Referring to Figure 1 the reference numeral 10 denotes the working bench or table to which is suitably secured a base plate 11. The bench is apertured as at 12 and in the 60 aperture is secured a needle sleeve 13 to the top of which a needle guide 14 is secured. The screws or bolts and the like for securing the various parts together are omitted for the sake of clearness. In said 65 needle sleeve moves a plunger 15 which is operated from the treadle 16, Fig. 2, by means of suitable treadle rods 17 and 18. The lengths of the treadle rods may be adjusted by a clamp 19 and bolts 20, 20 70 as shown. A spring 21 keeps the plunger 15 in inactive position. The treadle is pivoted at 22 in a foot 23 in such a manner that it may be easily lifted out of said foot and laid on the floor to prevent accidental 75 operation of the needle as will be understood.

The plunger 15 carries a needle 25 which is removably secured by a set screw 26.

On the base plate 11 is mounted a bracket 80 27 in which is pivoted at 28 an arm 29 provided with a handle 30 and a needle throat plate 31 having a cut out or aperture 32 for observing the mark on the garment. The arm 29 carries an adjustable stop 34 85 adapted to rest upon a yielding adjustable stop 35 secured in the bracket 27. 36 is a spring which tends to raise the stop 35. 45 is a stop on the arm 29. When the arm is raised to adjust the work, the stop 45 90 abuts the bracket 27.

The operation is as follows: First the treadle is depressed sufficiently to raise the needle 25 above the plate 11 to enable the operator to thread the needle with thread 95 from a spool 40 carried on the bracket 27. Thereafter the needle is lowered. Next the layers of fabric 41 are placed under the needle throat plate 31 so that the marking on the fabric may be observed through the aperture 32 which coincides in vertical alignment with the needle 25 as will be understood. When the garments have been accurately positioned as indicated in dotted lines, the handle 30 is depressed to clamp the garments firmly in position, during which part 100 of the operation the stop 34 depresses the stop 35.

Next the treadle is operated and the needle forced up through the garments, or in other words, the operator sews a stitch through the garments. The handle is then lifted, 5 the operator catches the end of the thread, the treadle is released and the needle descends. The result of this operation is a stitch through all the garments at the point which it is desired to mark. Thereafter 10 the thread is cut off from the spool, preferably adjacent the fabric and after these have been removed, the thread is cut off on both sides of each layer, this leaving a bit of thread as marking point.

15 The operation is very simple and may be expressed as follows: Thread the needle, position the garment, sew the stitch, catch the top of the thread, withdraw the needle, cut off the thread and remove the garments.

20 Figure 5 shows a modification in which the needle catches the thread from above. In this case a needle like the one shown in Figure 6 is used. The construction of the machine is similar to the one shown in Figure 1 except that the needle plate 50 preferably is longer and provided with the needle cut out 51, a thread guide 52 and a thread catch or fastener at 53. The thread 75 passes from a spool 54 through a guide 55, thence through the guide 52, across the cut out 51 and is temporarily fastened at 53 as shown. A tension device 50 may be employed to keep the thread taut. The operation is as above described except that the 25 needle is not threaded. After the garments have been placed in position, the treadle is depressed, the needle 65 in Figure 6 is forced up through the garments and catches the thread above the latter as it is stretched 30 across the opening at 51. Thereafter the treadle is released, the needle descends with the thread and thus a stitch is sewn through the garments. The garments are then lifted and the thread cut off beneath them and 35 above them and thereafter they are removed.

40 By adjusting the two stops 34 and 35 the normal position of the arm 29 is fixed to accommodate the height of the layer of garments operated upon.

45 50 I claim:

1. In a garment marking machine the combination with a horizontally disposed work support having a needle opening, of a needle mounted below the work support to reciprocate in a vertical plane and to move upwardly through said opening and to penetrate said work, and a manually controlled device cooperating with the work support to clamp the work therebetween during the upward movement of the needle.

55 60 65 2. In a garment marking machine, the combination with a horizontally disposed work support having a needle opening, of a needle mounted below the work support to reciprocate in a vertical plane and to move

upwardly through said opening and to penetrate said work, a manually controlled device cooperating with the work support to clamp the work therebetween during the upward movement of the needle, and a 70 needle throat plate fixed to said clamping device for cooperation with the needle.

3. In a garment marking machine, the combination with a horizontally disposed work support having a needle opening, of a 75 needle mounted below the work support to reciprocate in a vertical plane and to move upwardly through said opening and to penetrate said work, a spring for normally retaining the needle below the work support, 80 manually controlled means for moving the needle upwardly against the tension of said spring, and a device cooperating with the work support to clamp the work therebetween during the upward movement of the 85 needle.

4. In a garment marking machine, the combination with a horizontally disposed work support having a needle opening, of a needle mounted below the work support to reciprocate in a vertical plane and to move upwardly through said opening and to penetrate said work, and a manually controlled device cooperating with the work support to clamp the work therebetween during the upward movement of the needle, said device including a lever pivoted at one end at a point remote from the needle to provide a resultant and relatively large space thereunder for the work.

5. In a garment marking machine, the combination with a horizontally disposed work support having a needle opening, of a needle mounted below the work support to reciprocate in a vertical plane and to move upwardly through said opening and to penetrate said work, a manually controlled device pivoted to the work support and cooperating with the latter to clamp the work therebetween, and a spring for normally holding said device in an elevated position.

6. The combination of a base, a needle sleeve supported below the same, a plunger in said sleeve, a needle removably held by said plunger, means for maintaining the needle in a predetermined inactive position beneath the said base, a bracket secured to the base, a clamping arm pivoted to said bracket above the base, means for maintaining said clamping arm in a predetermined position above the base, means for adjusting said maintaining means, a handle in said clamping arm, a needle throat plate carried by the latter, said clamping arm being adapted to be operated to clamp garments between said needle throat plate and the said base in predetermined relationship with respect to the said needle and means for operating the latter upwards through the said clamped garments and the said needle

throat plate to mark the said garments with a thread in a predetermined position.

7. The combination with a work bench, a needle sleeve fitted into the said bench and depending therefrom, a base plate having a needle guide in alignment with said needle sleeve, a needle movably supported within said sleeve, an operating arm pivoted to said base, a needle throat plate secured to the free end of said operating arm, a handle for operating said throat plate to clamp the work between said plate and the said base, means for operating said needle upwardly through said needle guide and the work and a spring for automatically releasing the needle from the work.

8. The combination of a base, a needle, needle supporting and operating means mounted beneath said base, a bracket secured to the latter above the same, an arm pivoted to said bracket and extending forwardly over the said base, a needle throat plate secured to said arm in alignment with said needle, an adjustable yielding stop for normally maintaining said arm out of contract with said base, means for operating said arm and

throat plate to clamp the work between the latter and the said base and means for actuating said needle operating means to drive said needle upwardly through the work and the throat plate and a spring for returning said needle to normal position below the said base.

9. The combination of a base having an aperture, a needle, needle guiding means located below said base, a bracket secured to said base above the same, an arm pivoted to said bracket, a spool of thread on the latter, means for operating said needle upwardly through the said aperture in the base for threading said needle from the said spool of thread, means for automatically returning the threaded needle to normal position below said base, means pivoted to said bracket for clamping the work between said means and the said base, a handle for operating said clamping means to clamp the work as aforesaid, said needle operating means also serving to operate the threaded needle upwardly through the work to mark the same with a thread for the purpose set forth.

FREDERICK M. LASERSON.
